UNITED STATES PATENT OFFICE.

ANTON AXEL ANTHONY, OF MEMPHIS, TENNESSEE.

SWING CHAIR AND BED

Application filed December 18, 1924. Serial No. 756,768.

To all whom it may concern:

Be it known that I, ANTON AXEL ANTHONY, a subject of the King of Norway, and a declarant citizen of the United States, 5 residing at Memphis, in the county of Shelby and State of Tennessee, have invented a new and useful Swing Chair and Bed, of which the following is a specification.

This invention aims to provide a combined chair and bed, so constructed that a person may sit up or recline, novel means being provided for mounting the device in such a way that the same will not be much affected by 15 the movement of the support wherewith the structure is assembled, the article being of peculiar utility on a vessel, to prevent persons from becoming seasick.

It is within the province of the disclosure 20 to improve generally and to enhance the utility of devices of that type to which the invention appertains.

Although a preferred form of the invention has been shown, it will be understood 25 that a mechanic, working within the scope of what is claimed, may make alterations, without departing from the spirit of the invention.

In the accompanying drawings:

Figure 1 shows in side elevation a device 30 constructed in accordance with the invention the same being arranged to serve as a bed, parts being broken away; Figure 2 is a top plan of the structure shown in Figure 1, parts being broken away; Figure 3 is an elevation wherein the structure is arranged 35 to serve as a chair; Figure 4 is a sectional view of the suspension means; and Figure 5 is a fragmental bottom plan showing a 40 portion of the combined bed and chair, and, particularly disclosing the latch mechanism.

The device comprises an end section 1 provided with a projecting foot rest 2. Plates 3 are secured to the sides of the section 1 45 near to the inner end thereof. The plates 3 have inwardly projecting sockets 4. A shaft 5 is located in the sockets 4. The shaft 5 is held in the sockets 4 by set screws 6 threaded into the sockets. The shaft 5 turns 50 at its ends in one end of a main section 7. The end section 1, thus, is hinged to the main section 7. In a similar way, a shaft 8 connects the section 7 with an auxiliary section 10, and a shaft 9 connects the section 55 10 with an end section 11. Toothed latch

wheels 12 are secured to the shafts 5, 8 and 9. Latches 14 are slideable in guides 15 on the sections 7, 10 and 11. The latches 14 have heads 16 adapted to cooperate with the teeth of the latch wheels 12. Each latch 14 60 has an abutment 17. A spring 18 surrounds a portion of each latch 14 and engages the abutment 17 and one guide 15 to maintain the head 16 yieldably engaged with the latch wheel 12. Each latch 14 has a finger 65 piece 19 facilitating the manipulation of the latch. Guides 20, are mounted on the bottom of the sections 7, 10 and 11. Bolts 21 are mounted to slide in the guides 20 and have finger pieces 22 for their manipulation. 70 Posts 23 are mounted on the main section 7 at opposite sides thereof. Posts 24 are mounted on the end section 11 at opposite sides thereof. Links 25 are pivoted to the posts 23. Links 26 are pivoted to the posts 75 24. The links 25 and 26 are connected by a rule joint hinge 27. A curtain 28 is located at each side of the device, the curtains being carried by the parts 24, 26, 25, and 23. 80 The curtains 28 preferably are painted blue or, in any event, they are so constructed that a person cannot see through them readily.

A suspension means is provided. The suspension means includes upstanding posts 29 connected to each side of the main section 7. A spider 30 is secured to the upper ends of the posts 29. A plunger 31 is connected to the intermediate portion of the spider 30. The plunger 31 reciprocates in a cylindrical casing 32. The plunger 31 90 has a head 33 mounted to reciprocate in the casing 32. A compression spring 34 surrounds the plunger 31 and is located in the casing 32. One end of the spring 34 abuts against the head 33, and the other 95 end of the spring abuts against the bottom of the casing. A spindle 35 is secured to the top of the casing 32. The spindle 35 carries a ball 36. The ball 36 is mounted to rotate and to rock on ball bearings 37 100 located in races 38 formed in a hollow inverted frusto-conical bracket 39 secured at 40 to an overhead support of any kind, which may be the deck of a vessel, designated at 41.

The spring 34 supports the device yieldingly, and the balls 36 can rock and roll on the bearings 37. The result is that a person occupying the device will not participate to any great extent in the rolling or 110

plunging motion of a vessel whereon the device is located. The curtains 28 prevent the occupant from looking sidewise and seeing articles, such as chandeliers and the like, which may be swinging in the vessel, it being a matter of common knowledge that the sight of swinging objects often will upset a person who, otherwise, would not be subject to seasickness.

- 10 When the device is arranged as shown in Figure 3, it may be used as a chair. By pulling back the latches 14 out of engagement with the latch wheels 12, the parts 1—7, 7—10, and 10—11 may be located at 15 any desired angle with respect to each other, so that the structure may assume any position intermediate the chair, as shown in Figure 3, or a bed, as shown in Figure 1. When the latches 14 are released, they 20 will engage again with the latch wheels 12 under the action of the springs 18. In order to provide absolute security, when all of the parts 1—7—10—11 are in alignment, as shown in Figure 1, the bolts 21 may be 25 shot forwardly, beneath the parts 1, 7, 10 and 11, or to make the device absolutely rigid. It will be observed that the curtains 28 remain in place and assume their position automatically, regardless of whether the device is arranged as a chair, as shown in Figure 3, and as a bed as disclosed in Figure 1. Cushions 42, of course, may be used wherever desired.

I claim:—

- 35 1. In a device of the class described, a support for an occupant, means for suspending the support yieldingly, said means comprising a casing, a plunger adapted for reciprocation within said casing, a head upon said plunger, and a spring encircling said plunger between said head and an end of said casing, and means for suspending the support for universal swinging movement.
- 45 2. In a device of the class described, a support for an occupant, mechanism for hanging the support yieldingly, said mechanism comprising a casing, a plunger adapted for reciprocation within said casing, a head upon said plunger, and a spring

encircling said plunger between said head and an end of said casing, a ball carried by said mechanism, and a hanger-bracket wherein the ball is mounted for free rocking movement and for rotation.

3. In a device of the class described, a support for an occupant, the support comprising hingedly connected parts, posts upstanding from two of said parts, links pivoted to the posts, the links being pivotally connected, and a curtain carried by the posts and by the links.

4. A combined chair and bed yieldingly suspended for universal swinging movement, comprising a seat section, a foot-rest section hingedly connected with said seat section, a back-rest section hingedly connected with said seat section, a head-rest section hingedly connected with said back-rest section, and means at the respective junctions of the adjoining sections for holding each of said parts selectively in different angular positions relative to the adjacent part.

5. In a device of the class described, a support for an occupant, the support comprising hingedly connected parts, a latch wheel carried by one of said parts, a spring-actuated latch on the other of said parts, and adapted to cooperate with the latch wheel to hold said parts in adjusted positions, and a bolt slidable on one of said parts, the bolt being slidable to extend beneath another of said parts, thereby to hold the said parts in alignment.

6. A combined chair and bed suspended for universal swinging movement, comprising a seat section, a back-rest section hingedly connected with said seat section, a head-rest section adjustably connected with said back-rest section, posts upstanding from said seat section standards secured to said head-rest section, links connecting said posts and said standards and a curtain supported by said posts, said standards and said links.

In testimony that I claim the foregoing as my own, I have hereto affixed my signature.

ANTON AXEL ANTHONY.
